DESIGN FOR A FINGER RING

Aaron Koenig, Far Rockaway, N. Y.

Application May 19, 1944, Serial No. 113,687

Term of patent 14 years

(Cl. D45—10)

To all whom it may concern:

Be it known that I, Aaron Koenig, a citizen of the United States and a resident of Far Rockaway, in the county of Queens and State of New York, have invented a new, original, and ornamental Design for Finger Ring, as shown, of which the following is a specification, reference being had to the accompanying drawing, forming a part thereof.

The dominant features of my design are shown in full lines.

I claim:

The ornamental design for a finger ring, as shown and described.

AARON KOENIG.
